UNITED STATES PATENT OFFICE.

ORIN W. CLIFFORD, OF NORTH ATTLEBORO, MASSACHUSETTS, ASSIGNOR TO WEBSTER COMPANY, OF NORTH ATTLEBORO, MASSACHUSETTS, A CORPORATION OF RHODE ISLAND.

CIGARETTE-CASE.

1,184,166.

Specification of Letters Patent. Patented May 23, 1916.

Application filed March 24, 1916. Serial No. 86,412.

To all whom it may concern:

Be it known that I, ORIN W. CLIFFORD, a citizen of the United States, residing at North Attleboro, in the county of Bristol 5 and State of Massachusetts, have invented a new and useful Improvement in Cigarette-Cases, of which the following is a specification.

This invention relates to certain new and 10 useful improvements in cigarette cases, and the primary object of the invention is to provide a case in which a holder is provided that is composed of a pair of independently mounted parts each of which has or is 15 capable of movement independent of the other, and each of which is tensioned independently of the other.

Still further, the invention aims to provide a novel and simple means for tensioning the two holder parts and the two case 20 parts and to otherwise simplify and decrease the cost of production of cases of the general type set forth.

In the drawings—Figure 1 is a top plan 25 view, the case being completely open. Fig. 2 is a section on the line 2—2 of Fig. 1. Fig. 3 is a similar view on the line 3—3 of Fig. 2.

The case is composed of a front 1 and back 2 connected by hinge knuckles 3 to a 30 hinge pintle 4. The holder is composed of two similar sections or parts 5 having confronting and registering cigarette seats 6 as depicted in Fig. 1.

Each of the sections 5 has a pair of 35 depending or outwardly extending shanks 7 which are formed, preferably, integral with the holders as shown. The shanks 7 are formed with preferably single knuckles 8 which are engaged by the pintle 4, the 40 shanks having bottom parts 9 spaced from the knuckles 3 so that the sections 5 may swing to and fro without interference with or from the knuckles 3. For the purpose of not only tensioning the two sections 5, 5, 45 but also for the purpose of tensioning the

front and back of the case, a pair of coil springs 10 are employed, which springs are coiled about the pintle 4, and have their ends extending upwardly at 11 to engage the outer side faces of the sections 5 and 50 downwardly at 12, to engage the front and back of the case. As shown in Fig. 2, the shanks 7 are spaced apart permitting the upwardly extending ends 11 of the springs to project into or through this space. In 55 operation, either of the two sections 5 or both may be moved to admit cigarettes therebetween, and the act of opening or releasing the catches C enables the springs to automatically move the front and back to 60 lie in the same plane, with the holder extending at right angles to the front and back, which thus enables the use of but two springs to tension each of the two sections and both the front and back. 65

Having thus described my invention, what I claim as new and desire to secure by Letters Patent is—

In a cigarette case, a front, a back, each having hinge knuckles, a pintle passed 70 through the knuckles, a holder composed of two sections each formed with a contracted shank, the shanks having knuckles engaged with said pintle and having cut-away parts which overlie the front and back knuckles, 75 said shanks being spaced apart, and a pair of coil springs on the pintle, separated by one of the knuckles of the front or back and having upwardly extending ends which engage through the space between the shanks, 80 the opposite sides of the respective sections and having downwardly extending ends which engage the front and back.

In testimony whereof I have signed my name to this specification in the presence 85 of two subscribing witnesses.

ORIN W. CLIFFORD.

Witnesses:

ADA E. HAGERTY,
J. A. MILLER.
